CHARGE FORMING DEVICE

Application filed June 17, 1930. Serial No. 371,465.

This invention relates to charge forming devices, more particularly to that type of charge forming device which comprises a plurality of secondary mixing chambers located adjacent the engine intake ports, which are supplied with a primary mixture of fuel and air by a plurality of primary carburetors associated therewith and under certain operating conditions are supplied with additional mixture to be mixed with the primary mixture therein.

An example of a charge forming device of this character is disclosed in the copending application of Fred E. Aseltine and Wilford H. Teeter, Serial No. 221,371, filed September 22, 1927.

The primary object of the present invention is to improve the means for supplying fuel and air in a device of this character, for the purpose of improving the mixture proportioning under certain operating conditions, more particularly for improving the mixture proportions during the acceleration period following opening movements of the throttle.

With this object in view the principal feature of the invention resides in the provision of means controlled by the suction within the carburetor and operative to prevent the enrichment of the mixture to too great an extent when the throttle is moved from substantially closed positions to relatively wide open positions.

Further objects and advantages of the present invention will be apparent from the following description, reference being had to the accompanying drawings wherein a preferred embodiment of one form of the present invention is clearly shown.

In the drawings:

Fig. 1 is a vertical longitudinal section through a charge forming device according to the present invention and an intake port with which it is associated.

Fig. 2 is a transverse vertical section on the line 2-2 of Fig. 1.

Fig. 3 is a detail view of the auxiliary fuel chamber.

The device disclosed comprises a main air manifold 10 having three outlet branches, the

middle branch 12 being shown herein. Each of these branches communicates with one of the intake ports 14 of a multi-cylinder engine. These outlet branches are each provided with an attaching flange 16 for securing the manifold to the engine block in the usual manner. Adjacent the inlet of the manifold is provided a flange 18 to which the main carburetor unit is adapted to be attached, as shown in Fig. 1.

The carburetor unit comprises a main housing 20 having an attaching flange 22 adapted to be secured to flange 18 by screws 24. The air inlet coupling 28 is secured in position to register with an opening in the upper wall of the housing 20 in any suitable way and an air cleaner may be connected thereto if desired. A casting 30, in which the passages conducting fuel from the fuel bowl to the nozzles are formed, is secured by screws to the bottom wall of housing 20, and a sheet metal fuel bowl 32 is held tight against an annular shoulder 34 on said housing by any suitable means. Fuel is conducted from a main source of supply to the fuel bowl through a conduit not shown herein and the flow of fuel to the bowl is controlled by a float 36, operating in the usual manner to maintain a substantially constant level of fuel therein.

Fuel flows from bowl 32 to a plurality of primary fuel nozzles 38, one of which is located in each of the primary mixing chambers 40, the construction of which is briefly described hereinafter. The fuel conduit between the fuel bowl and the nozzles comprises a vertical fuel passage 42 communicating at its upper end with a horizontal fuel canal 44, which connects with each of the nozzles 38 through orifices 46. Fuel is admitted from the fuel bowl to passage 42 at all speeds through a fixed metering orifice 48 and at high speeds additional fuel is admitted through an orifice 50, controlled by a valve 52 in the manner set forth in the above mentioned application.

Fuel is lifted from the fuel bowl through the above described fuel passages and nozzles 38 to the mixing chambers by the suction therein. Closing movements of the throttle

cause a reduction in mixing chamber suction, which might permit the fuel column to drop sufficiently to cause a temporary fuel starving of the engine unless means were provided to prevent it. For this purpose a check valve 54 is provided in an enlarged chamber 56 at the junction of channels 42 and 44, and on reduction of mixing chamber suction seats on the bottom of its chamber, preventing downward flow of the fuel.

Each primary fuel nozzle is provided with a main fuel outlet 58 in the top of the nozzle and a secondary fuel outlet comprising two orifices 60 and 62 in the vertical wall of the nozzle near the bottom of the mixing chamber. At relatively high speeds the mixing chamber suction is enough to lift fuel from the main outlet as well as from orifices 60 and 62. At idling, or low speed operation under load, however, the suction is sufficient to lift fuel only to some point between the top of the nozzle and orifices 60 and 62, fuel flowing from these orifices by action of gravity. Each nozzle is provided with a restricted fuel metering orifice 63. The primary mixing chambers comprise the enlarged anterior ends of primary mixture passages 64, which are parallel to each other and close together as indicated in the drawings. When the carburetor is attached to the manifold, these passages register with conduits which convey the primary mixture to the secondary mixing chambers, as fully disclosed in the copending application referred to. Restrictions 66 separate the primary mixing chambers from the remainder of the mixture passages.

A single throttle valve 68, which extends across all the primary mixture passages, controls the flow therethrough and is provided with grooves 70, which register with said mixture passages. This throttle is operated by means fully disclosed in the above copending application and which forms no part of the present invention. The middle primary mixture passage communicates with a tube 72, fixed in the manifold branch 12, which conveys the primary mixture to the secondary mixing chamber in that branch of the manifold.

Substantially all the air entering the carburetor flows through the coupling 28, controlled by a main air valve 74, normally held against a seat 76 by a spring 78 received between the valve and a flange 80 projecting from a sleeve 82 slidably mounted on a stationary guide sleeve 84, fixed in the housing 20, and serving as a guide sleeve for the stem 86 to which the air valve is secured.

When it is desired to choke the carburetor to facilitate starting the flange is adapted to be lifted by means not shown herein but fully described in the above mentioned application, until the upper end of the sleeve 82 engages the valve to hold it closed. Suf-

cient air to carry the starting fuel from the nozzles to the intake ports is admitted through an elongated slot 90 formed in a plate 92 secured to the housing 20 as shown in Fig. 1.

The coupling 28 supplies air directly to a main air chamber 94 from which it flows to the primary mixture passages through an orifice 96 in the floor of the air chamber and to the secondary mixing chambers through a passage 98, which connects with the inlet of the manifold 10. A manually operable throttle 100, secured to a shaft 102 and operated by the primary throttle operating mechanism in a manner hereinafter briefly described controls the flow of air through the passage 98. The throttle operating mechanism forms no part of the present invention but is fully shown and described in the prior copending application.

On opening of either or both the throttle valves the suction in the air chamber is increased and the air valve is opened against the tension of its spring to admit additional air and increase the quantity of mixture supplied the engine. The opening of the valve is retarded temporarily however, to supply an enriched mixture during the acceleration period immediately following the throttle opening movement, and also to prevent fluttering of the valve. The retarding means comprises a dashpot comprising a cylinder 106 formed in the casting 30, and a piston 108 clamped between a flange 110 on a coupling 112 secured to the lower end of the air valve stem and a nut 114 screwed on the coupling. A check valve (not shown) may be provided in the bottom of the dashpot to admit fuel to the cylinder on upward movement of the piston and prevent escape of fuel from the cylinder on downward movement of the piston. This dashpot is of conventional form and the structural details constitute no part of the present invention.

In order to facilitate understanding of the operation of this invention the mode of operation of the throttles will now be very briefly described. As above stated the primary throttle operating mechanism is adapted to operate the air throttle 102 but a lost motion connection is provided in the operating connections which permits an initial opening movement of the primary throttle without accompanying movement of the air throttle, after which the throttles move simultaneously. Preferably the construction is such that the primary throttle is permitted to open independently of the main throttle until the engine is running at a speed corresponding approximately to a vehicular speed of 20-25 miles per hour on a level.

It has been found that the dashpot, in order to enrich the mixture sufficiently for satisfactory acceleration on all opening movements of the throttle temporarily must re-

tard the air valve so much that under some conditions the suction at the nozzles builds up to a such a degree that the mixture temporarily becomes too rich resulting in "loading" of the engine. As an example of conditions under which the dashpot is effective to produce too rich a mixture to be suitable, it may be assumed that the throttle is opened from a relatively closed position to a relatively wide open position as frequently occurs at the end of a coast. The engine is already running fast and there is no substantial increase in speed nor is any great increase in richness of the mixture desired. However, there is a very great increase in suction at the fuel nozzles temporarily and unless means is provided to compensate therefor, the mixture becomes too rich.

To eliminate these difficulties means are provided, according to the present invention, to regulate the mixture enrichment by the suction in the main air chamber 94. This means comprises an auxiliary fuel chamber 120 positioned above the fuel level in the main fuel chamber. This chamber is sealed against admission of air any suitable air tight joint being provided between the chamber and its top 122. The latter is provided with an upstanding lug 124 adapted to be attached to the casting 30 by a screw 126. If desired the chamber 120 could be formed in the casting 30, integral therewith. Screwed into the bottom of the chamber 120 or connected therewith in any other suitable manner is a pipe 128, the other end of which is connected to the fuel supply passage between the valve 52 and the vertical passage 42 as shown in Fig. 2. A union or other suitable coupling means may be provided in the pipe 128 to facilitate assembly of the parts. A suction conduit 130, which may be formed as one piece or in two parts joined by the union 132, is connected at one end to the upper part of the chamber 120, and the other end projects through the wall of the housing 20 into the main air chamber 94. A nipple 134 is screwed into the pipe 130 to admit air thereto, for the purpose of controlling the suction communicated by such pipe to the chamber 120.

The device operates in substantially the following manner. It may be assumed that the vehicle is being operated at a speed of 15-20 miles per hour. If the throttles are opened further to increase the speed relatively slightly, for example to 30-35 miles per hour, the suction at the fuel nozzles is increased during the temporary retardation of the opening movement of the air valve, so as to increase the fuel flow to enrich the mixture to the extent necessary for smooth acceleration but the suction does not increase sufficiently to form too rich a mixture. If, however, the throttles are opened from a relatively closed position, either when running fast

at the end of a coast or when running slowly under load, to a relatively wide open position, the suction at the fuel nozzles is built up so greatly while the dashpot resists the opening of the air valve that there is a very great increase in suction at the fuel nozzles which would result in too much enrichment of the mixture causing "loading" and irregular engine operation.

The suction of the air chamber 94 is communicated to the chamber 120 and tends to draw fuel from the fuel supply passage leading to the nozzles, through the pipe 128 into the chamber 120 and if effective to draw fuel from the said passage will reduce the amount of fuel which would otherwise be supplied to the nozzles. At any fixed throttle position when the air valve is in a condition of balance the suction communicated to the chamber 120 is not sufficient to draw fuel from the passage 42 to such chamber. In fact, due to the admission of air through the nipple 134 the pressure in the suction passage and chamber 120 is little less than atmospheric under those conditions. Moreover, the supply of air through the nipple 134 is such that the suction within the suction passage and chamber 120 is not increased sufficiently on opening of the throttle under the conditions first described above to draw fuel from the passage 42, because as above set forth, the mixture enrichment is not too great under such operating conditions.

When the throttle is opened from nearly closed position to relatively wide open position, however, the suction in the air chamber 94 increases enough to create sufficient suction in chamber 120 to draw fuel into such chamber from the passage 42, notwithstanding the admission of air through the vent. This will cause the nozzles to deliver a less amount of fuel than would otherwise have been supplied as a result of the temporary increase in suction at the nozzles whereby a mixture of proper proportions is supplied.

The fuel drawn into the chamber 120 in the manner above described is retained in said chamber only so long as the suction effective in said chamber is sufficient to support a column of fuel extending that much above the normal fuel level. As soon as the suction becomes insufficient to support such a column of fuel, the fuel in said chamber flows back into the fuel passage 42, slightly augmenting the fuel flow from the nozzle until the column of fuel in the conduit 128 falls to the point where it is balanced by the suction effective on said column. It will be clear that the device above described is effective to prevent the mixture being enriched too much at any one instant and is also effective to prolong the total period of mixture enrichment. This action is obviously beneficial when the throttle is opened through relatively great

distances because under these circumstances the acceleration period is correspondingly longer and enrichment is needed for a longer time.

- 5 It will be understood that the nipple 134 is removable and nipples having an air passage of different size may be employed. By varying the size of the passage admitting air to the conduit 128 the suction communicated to 10 the chamber 120 from the air chamber may be varied to regulate as desired the effect of the device on the flow of fuel from the nozzles. By reducing the amount of air admitted to conduit 128, fuel is drawn from the 15 passage 42 on lesser increases in suction in the air chamber while increasing the size of the air vent to the passage 128 will have the opposite effect.

A secondary mixing chamber is associated 20 with each outlet branch of the manifold, one of such mixing chambers being shown herein. Each mixing chamber comprises a Venturi tube 140, having an external rib 142 clamped between shoulders 144 and 146 on 25 the manifold and the engine block respectively, when the device is assembled. These Venturi tubes are so positioned that the outlet of each primary mixture conduit is positioned at the point of greatest suction in the 30 venturi associated therewith. These Venturi tubes constitute no part of the present invention but function in a manner fully set forth in the above application.

While the form of embodiment of the present 35 invention as herein disclosed, constitutes a preferred form, it is to be understood that other forms might be adopted, all coming within the scope of the claims which follow.

What is claimed is as follows:

- 40 1. A charge forming device for internal combustion engines comprising a mixture passage, a fuel inlet therefor, an air chamber for supplying air to said mixture passage, a throttle, means operative on opening movements of the throttle for enriching the mixture during the acceleration period, and means controlled by the suction within the air chamber for modifying the action of said mixture enriching means.
- 45 2. A charge forming device for internal combustion engines comprising a mixture passage, a fuel inlet therefor, an air chamber for supplying air to said mixture passage, a throttle, means operative on opening movements of the throttle to temporarily restrict the air supply and increase the suction at the fuel inlet, whereby the flow of fuel therefrom is temporarily increased to enrich the mixture during the acceleration period, and means controlled by the suction within the air chamber to modify the normally increased flow of fuel resulting from increased suction at the fuel inlet under certain operating conditions.
- 50 3. A charge forming device for internal

combustion engines comprising a mixture passage, a fuel inlet therefor, an air chamber for supplying air to said mixture passage, a throttle, means operative on opening movements of the throttle to temporarily restrict the air supply and increase the suction at the fuel inlet, whereby the flow of fuel therefrom is temporarily increased to enrich the mixture during the acceleration period, and means controlled by the suction within the air chamber when the throttle is opened from a substantially closed to a relatively wide open position to restrict the fuel flow, whereby the very high suction produced at the fuel inlet on such a movement of the throttle is prevented from causing too much enrichment of the mixture.

4. A charge forming device for internal combustion engines comprising a mixture passage, a fuel inlet therefor, an air chamber for supplying air to said mixture passage, a throttle, means operative on opening movements of the throttle to cause a temporarily increased flow of fuel from the nozzle for enriching the mixture during the acceleration period, and means controlled by the suction within the air chamber for reducing the flow of additional fuel supplied for mixture enrichment while prolonging the period during which the mixture is enriched.

5. A charge forming device for internal combustion engines comprising a mixture passage, a fuel inlet therefor, an air chamber for supplying air to said mixture passage, a throttle, means operative on opening movements of the throttle to temporarily increase the suction at the fuel inlet to cause an increased flow of fuel therefrom and means operative on certain opening movements of the throttle to simultaneously restrict the flow of fuel from said inlet whereby too much enrichment of the mixture is prevented.

6. A charge forming device for internal combustion engines comprising a mixture passage, a fuel inlet therefor, an air chamber for supplying air to said mixture passage, a throttle, means operative on opening movements of the throttle to temporarily increase the suction at the fuel inlet to cause an increased flow of fuel therefrom and means controlled by the suction within the air chamber and operative on certain opening movements of the throttle to simultaneously restrict the flow of fuel from said inlet whereby too much enrichment of the mixture is prevented.

7. A charge forming device for internal combustion engines comprising a mixture passage, a fuel inlet therefor, an air chamber for supplying air to said mixture passage, a throttle, means operative on opening movements of the throttle to temporarily increase the suction at the fuel inlet to cause an increased flow of fuel therefrom and means

operative on certain opening movements of the throttle to restrict the flow of fuel from said inlet, said means comprising a suction conduit extending from the air supply chamber to the fuel passage leading to said fuel inlet.

8. A charge forming device for internal combustion engines comprising a mixture passage, a fuel inlet therefor, an air chamber for supplying air to said mixture passage, a throttle, a fuel supply passage leading to said fuel inlet, a throttle, means operative on opening movements of said throttle for increasing the flow from said fuel inlet to enrich the mixture for acceleration and means for modifying the effect of said last mentioned means on certain opening movements of the throttle, and means comprising a suction passage connecting the fuel supply passage with the intake passage at a point anterior to the throttle.

9. A charge forming device for internal combustion engines comprising a mixture passage, a fuel reservoir, a fuel inlet in said mixture passage, a fuel supply passage connecting said inlet with the fuel reservoir, a throttle, an air chamber for supplying air to said mixture passage, means operative on opening movements of the throttle to increase the flow from said fuel inlet in order to enrich the mixture during the acceleration period; an auxiliary fuel chamber, a conduit connecting said chamber with the fuel supply passage, and means effective on certain opening movements of the throttle to effect a flow of fuel from the said fuel passage to said auxiliary chamber.

10. A charge forming device for internal combustion engines comprising a plurality of secondary mixing chambers, a plurality of primary mixing chambers supplying a primary mixture of fuel and air thereto, fuel inlets therefor, an air chamber supplying air to all of the primary and secondary mixing chambers, a throttle regulating the flow from all of said primary mixing chambers, means operative on opening movements of the throttle for increasing the flow from said fuel inlets during the acceleration period, and means controlled by the suction in the air chamber and operative on certain opening movements of the throttle for modifying the action of said mixture enriching means.

11. A charge forming device for internal combustion engines comprising a plurality of secondary mixing chambers, a plurality of primary mixing chambers supplying a primary mixture of fuel and air thereto, fuel inlets for supplying fuel to said primary mixing chambers, a fuel reservoir, a fuel supply passage connecting said fuel reservoir with said fuel inlets, a throttle, an air chamber for supplying air to all of said primary and secondary mixing chambers, means operative on opening movements of the throttle

to increase the flow from said fuel inlets in order to enrich the mixture during the acceleration period and means effective on certain opening movements of the throttle to draw fuel from said passage whereby the degree of mixture enrichment is reduced.

In testimony whereof I hereto affix my signature.

FRED E. ASELTINE.
